(57) **CLAIM**

The ornamental design for a vertical stand for a video game console with cooling fan, as shown and described.

DESCRIPTION

FIG. 1 is a perspective view of a vertical stand for video game console with cooling fan showing my new design;
FIG. 2 is a front elevational view thereof;
FIG. 3 is a back elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is a perspective view of the vertical stand for video game console with cooling fan showing pull out game slots. The broken lines in the drawings depict part of the vertical stand for video game console with cooling fan that form no part of the claimed design.
